UNITED STATES PATENT OFFICE.

OSCAR JUNGGREN, OF SCHENECTADY, NEW YORK, ASSIGNOR TO GENERAL ELECTRIC COMPANY, A CORPORATION OF NEW YORK.

ELASTIC-FLUID TURBINE.

No. 826,941.

Specification of Letters Patent.

Patented July 24, 1906.

Application filed January 2, 1906. Serial No. 294,295.

To all whom it may concern:

Be it known that I, OSCAR JUNGGREN, a citizen of the United States, residing at Schenectady, county of Schenectady, State of New York, have invented certain new and useful Improvements in Elastic-Fluid Turbines, of which the following is a specification.

The present invention has for its object to improve the construction of elastic-fluid turbines.

In the accompanying drawings, which are illustrative of the invention, Figure 1 is a partial axial section of a multistage turbine; Fig. 2 is a plan view of the ring which forms a support common to a diaphragm and the intermediate buckets with an inclosing casing made in a single piece, and Fig. 3 is a partial longitudinal section wherein the parts are so arranged that the ring can be removed without making the casing in sections.

1 represents a cylindrical casing which is made in segments and secured together by bolts 2. This casing is mounted upon a base 3 or upon another section of the casing, depending upon the construction of the turbine. On the base is an internal shoulder 4, with which the ring 5 engages. The shaft of the machine in the present instance is vertically disposed; but it can be arranged horizontally under certain conditions, in which case suitable means would be employed to prevent the diaphragm from leaving its seat when the steam-pressure is removed. The upper surface of the ring is finished, and engaging therewith is a diaphragm 6. In this case the entire weight of the diaphragm and attached parts and the ring and attached parts is supported by the shoulder 4. The steam-pressure on the diaphragm will firmly seat it. The diaphragm is composed of a central portion 7 and an outer portion 8, the two parts being separated by a fluid-carrying passage 9 and united by strong radial ribs 10.

45 The under surface of the diaphragm is finished to receive the detachable sectional nozzle 11. This nozzle may be expanding or non-expanding in character and is arranged to convert the pressure of the motive fluid

50 into velocity and discharge it against the wheel-buckets 12. The buckets are arranged on the periphery of the wheel and are secured thereto by shoulders 13, engaging in grooves, and rivets or bolts 14. Between

the rows of wheel-buckets are intermediate 55 buckets 15, carried by an overhanging shoulder formed on the inside of the ring. Between the base of the intermediate buckets and the shoulder is a tongue and groove to center the parts. Bolts 16 pass through the 60 bucket-base into the ring from the under side. The intermediate buckets may extend entirely around the wheel, as in the present illustration, or they may extend only partially around. This depends upon which 65 stage the buckets are located in, the power of the machine, and other conditions that need not be mentioned.

With the arrangement shown in Fig. 1 the ring can only be removed by separating the 70 parts of the other cylindrical casing, whereas in Fig. 3 it can be removed without so doing, because the outside diameter of the ring is less than the inside diameter of the casing. The ring is provided with an internal groove, 75 into which the base of the intermediate buckets snugly fits. Suitable radially-extending bolts clamp the intermediates to the ring. Only one ring has been shown; but it is evident that it can be duplicated *ad libitum*. 80

In accordance with the provisions of the patent statutes I have described the principle of operation of my invention, together with the apparatus which I now believe to represent the best embodiment thereof; but 85 I desire to have it understood that the apparatus shown is only illustrative and that the invention can be carried out by other means.

What I claim as new, and desire to secure by Letters Patent of the United States, is— 90

1. In an elastic-fluid turbine, the combination of a casing, a diaphragm for dividing it into wheel-compartments, and a removable ring located inside of the casing which is separable from and engages the diaphragm and 95 maintains it in a definite position.

2. In an elastic-fluid turbine, the combination of a casing, a diaphragm for dividing it into wheel-compartments, fluid-discharging devices, and a removable ring located inside 100 of the casing, which forms a support common to the diaphragm and fluid-discharging devices.

3. In an elastic-fluid turbine, the combination of a casing, an internal shoulder on the 105 casing, a ring seated on the shoulder, a diaphragm supported by the ring and dividing the casing into wheel-compartments, and in-

termediate buckets carried by and secured to the ring.

4. In an elastic-fluid turbine, the combination of a casing, a diaphragm located therein for dividing it into wheel-compartments, intermediate buckets, and a ring of less diameter than the inside of the casing and removable therefrom, which forms a support com-

mon to the diaphragm and intermediate buckets.

In witness whereof I have hereunto set my hand this 21st day of December, 1905.

OSCAR JUNGGREN.
